THOMAS S. HUDSON, OF EAST CAMBRIDGE, MASSACHUSETTS.

Letters Patent No. 93,090, dated July 27, 1869.

IMPROVEMENT IN HAND-STAMPS.

The Schedule referred to in these Letters Patent and making part of the same.

To all whom it may concern:

Be it known that I, THOMAS S. HUDSON, of East Cambridge, in the county of Middlesex, and State of Massachusetts, have invented certain Improvements in Hand-Stamps, of which the following is a full, clear, and exact description, reference being had to the accompanying drawings, making part of this specification, in which—

Figure 1 is a front elevation of a hand-stamp with my improvements applied thereto.

Figure 2 is a central vertical section on the line $z z$ of fig. 1.

Figures 3, 4, and 5, details and modifications to be referred to.

My invention consists in indicating upon the frame of a hand-stamp, or upon a plate or other device attached thereto, a series of letters, figures, or characters, which shall serve as a guide for bringing into their proper position those required for stamping the impression, whether the guiding-letters, figures, or characters be stationary or movable, and whether they be placed upon the head of the frame or on its top or side, and whether their position be in a horizontal or vertical plane, or in a plane inclined thereto; and, in connection with the above,

My invention also consists in a movable or stationary calendar, bearing the names or portions of the names of the days of the week.

To enable others skilled in the art to understand and use my invention, I will proceed to describe the manner in which I have carried it out.

All the operating-portions of the stamp are constructed in any known way suitable for stamps of the kind.

In addition to these known devices, I provide the following features constituting my invention.

I is a circular metal plate, bearing the figures and letters representing the years, days of months, and other characters usually required in hand-stamps for printing dates, &c.

This circular plate revolves freely on an axis, consisting of a pin, m , screwed into the front of the head of the frame-work.

Fitting over a smooth portion of this pin, and secured immovably thereon by a spline and feather, is a segmental plate, K, bearing letters which serve as a calendar for representing the names of the days of the week.

An index, L, pointed at both ends, $n o$, is also fitted over the screw-pin, between the calendar-plate K and head of the pin, (see fig. 3,) the index being slipped loosely thereon, so as to be free to be moved by hand for the following purpose:

It being desired to stamp the date, "March 4, 1869," upon a slip of paper placed on the bed or table b , the

figures "69" are brought in line with the upper end, n , of the index L, when it will be seen that the lower end, o , of the pointer stands opposite the figures 74. Now withdraw the pin g from its position in one of the holes in the side of the year-wheel C, and hold it away from contact therewith while revolving the said wheel around, till the figures "74" are exposed to view at the top of the opening between the bifurcated portions of the plunger, just below the circular plate I, when the pin g may be allowed to spring back into one of its holes, and prevent the wheel from revolving.

The position of these figures (74) on the type-wheel D is such, that when at this point, the figures 69 will be found on the edge of this wheel, at its lowest point, ready for stamping its impression.

Next, turn the circular plate I around till the letters "Mar" are brought opposite the upper end, n , of the pointer, when the letters "Aug" will be found opposite the lower end, o , of the index or pointer L. Now withdraw and hold back the pin i from its hole in the wheel D, till it is revolved sufficiently to bring to view (opposite the figures 74) the letters "Aug" on the edge of said wheel, when the pin i is allowed to fall into its hole, and thereby prevent its revolution.

When these letters "Aug" are in the position above referred to, the letters "Mar" will be found on the edge, at lowest point of the wheel D, in their proper position for stamping their impression, and opposite the figures "69."

Next, bring the figure 4, on the circular plate I, around in line with the upper end, n , of the index or pointer L, and the figures 17 will be found in line with the lower end, o , of the pointer, when on withdrawing the pin h from its hole in the circular plate on the hub of the wheel E, and turning this wheel till the figures 17 are brought up to view in the line with "74" and "Aug," the pin h is allowed to be pressed back into its proper hole in the circular plate on the hub of the wheel E, thus preventing the middle wheel E from revolving, and the required figure, 4, will be found in its proper position for stamping the impression.

The figures representing the days of the month may be brought in line with the names of the days of the week corresponding thereto on the segmental plate or calendar K, by simply turning the circular plate I around until the proper figures are brought in line with the respective days of the week, occurring on those particular days of the month.

In the foregoing description, I have spoken of the circular plate I, and index or pointer L, revolving on their axis m , while the calendar K, representing the days of the week, was stationary thereon, but if desired, the circular plate I may be stationary, and the

calendar K and pointer L may revolve on the axis *m*, or the circular plate I and calendar K may both move and the pointer L be stationary.

Furthermore, the circular plate may be dispensed with, and its letters and figures be made directly on an enlargement of the head of the frame-work, as seen in fig. 4.

What I claim as my invention, and desire to secure by Letters Patent, is—

The plate I, with an indicator, L, in combination with the printing-wheels of a hand-stamp, substantially as and for the purpose described.

Also, a calendar-plate, K, in combination with the plate I, substantially as and for the purpose set forth.

THOS. S. HUDSON.
